UNITED STATES PATENT OFFICE.

CLIFFORD N. JOHNSON, OF TOLEDO, OHIO, ASSIGNOR TO THE CONKLIN PEN MANUFACTURING COMPANY, OF TOLEDO, OHIO, A CORPORATION OF OHIO.

MAGAZINE PENCIL.

Application filed December 31, 1921. Serial No. 526,182.

To all whom it may concern:

Be it known that I, CLIFFORD N. JOHNSON, a citizen of the United States, and a resident of Toledo, in the county of Lucas and State of Ohio, have made an Invention Appertaining to a Magazine Pencil; and I do hereby declare the following to be a full, clear, and exact description of the invention, such as will enable others skilled in the art to 10 which it appertains to make and use the same, reference being had to the accompanying drawings, and to the characters of reference marked thereon, which form a part of this specification.

15 This invention relates to pencils, and particularly to those of the magazine type employing a lead propelling and repelling mechanism including a helical tube and a longitudinal slotted tube fitted one within 20 the other.

The primary object of the invention is the provision of a simple, strong, durable and inexpensive pencil of the character described which is capable of having the parts thereof 25 easily and quickly assembled and secured together in a manner to facilitate a separation thereof to facilitate repair or inspection of the interior parts, thereby enhancing the practicability of pencils of this character.

30 A further object of the invention, is to simplify, cheapen and strengthen pencils of this class by making the fluted magazine tube and the longitudinally slotted tube forming a part of the lead propelling and 35 repelling mechanism in a single piece, which is preferably formed by extruding metal in cold form from a shaping die.

The invention is fully described in the following specification, and while in its 40 broader aspect it is capable of embodiment in numerous forms, a preferred embodiment thereof is illustrated in the accompanying drawings, in which,—

Fig. 1 is a side elevation of a pencil embodying the invention. Fig. 2 is an enlarged 45 central longitudinal section thereof. Fig. 3 is a side elevation of the spirally slotted tube of the pencil, with a tip engaging collar mounted on its forward end. Fig. 4 is a 50 side elevation of the internal tubes of the pencil in assembled relation with a part broken away. Fig. 5 is a cross-section on the line 5—5 in Fig. 2, and Fig. 6 is a cross-section on the line 6—6 in Fig. 4.

55 Referring to the drawings, 1 and 2 re-

spectively designate the barrel and tip members of a pencil embodying the invention, 3 a small helically slotted tube which is fixed at its forward end to the interior of the tip member 2 and extends rearwardly therefrom centrally through the barrel member to the rear end thereof, and 4 a longitudinally slotted tube which is mounted for free rotary movements on the tube 3 extending from the forward shouldered end of the tube 3 to a point adjacent the rear end thereof.

The longitudinally slotted tube 4 is provided in equidistantly spaced relation therearound with a plurality of radially projecting flutes or ribs 5, which extend longitudinal of the tube from a point near its rear end to a point near its forward end, the tubular portion of the tube being extended slightly beyond the rear end of the flutes to 75 form a threaded nipple 6 and being extended slightly beyond the forward end of the flutes to form the nipple or bearing extension 7. The flutes or ribs 5 on the tube 4 have a tight fit within the barrel 1, thereby 80 serving to frictionally retain the barrel in assembled engagement therewith. The fluted tube 4 cooperates with the barrel to form a series of lead receiving pockets 8 within the latter, said pockets, in the present instance, being three in number.

The forward end of the tube 3 is formed with a taper to fit the interior taper of the tip 2 and is rigidly secured to the tip by solder or in any other suitable manner. The 90 inner end of the tip 2 is mounted on a sleeve 9, which may be journaled for free turning movements on the nipple or bearing extension 7 at the forward end of the tube 4. The forward or inner end of the barrel preferably laps the sleeve 9 and has a turning fit thereon. If desired, both the barrel 1 and tip 2 may have a turning fit at their inner ends on the sleeve. A ferrule member 10 threads at its inner end on the nipple 6 100 of the tube 4 and has a turning fit in the outer end of the barrel 1. The ferrule 10 extends beyond the outer end of the barrel and is adapted to have a cap 11 removably mounted thereon to enclose an erasure rubber 12 which is mounted in the outer end of the ferrule.

A lead gripping sleeve 13 is mounted within the helically slotted tube 3 for reciprocal movements therein and is adapted 110

to have its forward end receive and frictionally grip the inner or rear end of a lead 14 mounted on the pencil so that the lead is caused to have reciprocatory movements therewith. The sleeve 13 has a stud 15 projecting laterally from its rear end through the helical slot 16 of the tube 3 and into the longitudinal slot 17 of the tube 4 so that a turning of one tube relative to the other will cause the sleeve 13 to move in one direction or the other longitudinally of the tube as is well understood in the art. A lead ejecting stem 18 projects into the rear end of the sleeve 13 and has its outer end angled to project through the helical slot 16 and into the longitudinal slot 17 so that the sleeve 13 and stem will travel together longitudinally of the tubes upon a relative turning thereof. The longitudinal slot 17 is provided at its forward end with a lateral extension 19 into which the stud 15 of the clutch sleeve 13 passes when it has reached the limit of its forward movement, thereby preventing it from having further forward movement while the stem 18 continues its forward movement to eject the lead from the sleeve. Nothing new is claimed for this method of propelling and retracting the lead, as it is old in the art.

30 The helically slotted tube 3 has its forward end tapered, as shown at 20, to provide it with an extended surface for feeding into the taper of the tip 2, and in order to facilitate a firm soldering of the tip to the tube 3, a tapered collar 21 is mounted on the forward end portion of the tube adjacent to the taper 20 thereof and adapted to fit the taper of the tip, thereby providing more surface for soldering contact with the tip than would otherwise be present. The tube 3 has spurs 22 struck from its sides near the taper 20 and these enter notches in the forward end of the collar 21 to retain the collar against turning relative to the tube. The rear end of the collar 21 forms a shoulder for abutting against the forward end of the tube 4 which is stationary with respect to the barrel 1. The helical slot 16 in the tube 3 extends from the collar 21 completely to the rear of the tube. When the tube 4 has been mounted on the tube 3 the tubes are retained together by a headed screw 23, which is threaded into the rear end of the helical tube 3 and has its head of sufficient size to lap the rear end of the tube 4, thereby preventing one tube from being withdrawn from the other. When the two tubes are assembled, with the tube 4 in abutment at its forward end with the collar 21, the rear end of the inner tube 3 will terminate slightly short of the adjacent end of the tube 4, as shown in Fig. 4. A turning of the screw 23 into the tube 3 with its head in contact with the rear end of the tube 4 causes a longitudinal tension to be

applied to the helical tube 3, which effects a stretching thereof and a slight transverse contraction due to the longitudinal stretching, thus causing the helical tube to act as a spring member and to cooperate with the screw to yieldingly retain the two tubes in close assembled relation.

Inasmuch as the tubes 3 and 4 have relative or opposed turning movements when a lead is being propelled or retracted, it would appear that the frictional engagement of the head of the screw 23 with the outer end of the tube 4 during such turning movement would tend to either tighten the screw in the helical tube 3 or to loosen the same, depending on the direction of relative turning of the tubes. This is not the case, however, as the stretching of the helical tube causes it to have a locking action on the threads of the screw 23 and to retain it in adjusted position.

In making pencils of this character, it has heretofore been the practice to provide a magazine tube separate from the slotted tube and enclosing the same, the magazine tube being of corrugated form to provide a plurality of lead receiving spaces between it and the pencil barrel. In the present pencil the longitudinal slotted tube and magazine tube are combined in one, the radiating flutes or ribs 5 on the longitudinally slotted tube being integral therewith and terminating short of its ends to provide nipples or bearing extensions at both ends of the tube, the tube 4 is preferably made in this form by applying pressure to a cold block or bar of metal and causing the metal to be extruded through a die in the form of a fluted tube, after which the flutes or ribs 5 are milled off at the ends of the tube to form the tubular end extensions 6 and 7. The tube is also milled to form the slot 17, 19 therein. This provides a tube which is of greater strength and rigidity than the combined slotted and magazine tubes heretofore used, and it materially simplifies the manufacture of such tubes and lessens the cost of same.

The barrel 1 is preferably secured in assembled position on the fluted tube 4 by extending the inner end of the spring 24, which carries the pocket engaging clip 25, through a side opening in the barrel and thence for a distance longitudinally of the barrel, between it and one of the ribs 5 of the tube 4 and providing its free end with an angled tail-piece 26 for engaging in a notch 27 in the coating rib 5. This method of locking the parts together is disclosed and claimed in my copending application Ser. No. 518,193 filed November 28, 1921.

In assembling the parts of a pencil embodying my invention, it is preferable to first assemble the slotted tubes 3 and 4 and to mount the lead holding and ejecting members 13 and 18 therein, the collar 9 being

mounted on the end extension 7 of the tube 4 before the mounting of such tube on the tube 3. The tip member 2 is then placed over the conical end portion 20, 21 of the tube 3 and heat is applied thereto around the surface 20, 21 to cause solder previously placed on such surface or on the inner surface of the tip to melt and securely unite the tube to the surfaces 20, 21. The barrel 1 is then forced over the fluted tube 4 the desired distance or until the inner angled end of the clip spring 24, which was previously inserted into position in the barrel has snapped into locking engagement with the notch 27 in the coacting rib 5. The ferrule 10 is then threaded onto the end 6 of the tube 4. The screw 23 may be adjusted either before or after the mounting of the barrel 1 on the tube 4, so as to apply the desired tension on the helical tube 3 to retain it in yielding assembled relation to the tube 4. It is apparent that the different parts of the pencil may be easily and quickly assembled without the use of any solder except at the point of connecting the tip 2 to the forward end of the helical tube 3, thereby facilitating manufacture and also the separation of the parts for repair or inspection.

I wish it understood that my invention is not limited to any specific construction, arrangement or form of the parts, as it is capable of embodiment in numerous forms without departing from the spirit of the claims.

Having thus described my invention, what I claim as new and desire to secure by Letters Patent, is,—

1. In a pencil of the class described, a helical tube, a tip fixed to the forward end of the tube, a longitudinally slotted tube rotatably mounted on the helical tube and having integral radial ribs extending longitudinally thereof, means coacting with the two tubes to retain them in assembled relation, lead actuating means disposed within the tubes in engagement with the slots thereof and actuated by a relative turning of the tubes, and a barrel mounted on the ribs of the longitudinally slotted tube.

2. In a pencil of the class described, inner and outer relatively rotatable slotted tubes, a tip and a barrel fixed to the said tubes respectively, a lead actuating mechanism enclosed within the tubes and operated by a relative turning thereof, the outer slotted tube having integral longitudinally extending ribs projecting outward therefrom and supporting the barrel, and means coacting with the tubes to retain them in assembled relation.

3. In a pencil of the class described, an inner helical tube having a shouldered forward end, an outer longitudinally slotted tube rotatably mounted on the helical tube in end abutment with the shouldered end

thereof, the outer tube having integral longitudinally extending ribs projecting outward therefrom in circumferentially spaced relation and terminating short of the ends of the tube to form tubular end extensions, 70 a collar mounted on the end extension adjacent to the shouldered end of the helical tube, means coacting with the rear ends of the two tubes to retain the tubes in assembled relation, a tip member fixed to the shouldered end portion of the helical tube and at its rear end embracing the collar, a barrel mounted on the ribs of the outer tube for turning movements therewith and extending at its forward end adjacent to the 80 tip, and a member extending into the rear end of the barrel and threaded on the rear end extension of the outer tube, and lead actuating means mounted within the tubes and actuated by relative turning movements 85 thereof.

4. In a pencil of the class described, a helically slotted tube and a longitudinally slotted tube mounted one on the other for relative turning movements and having 90 shouldered coaction at one end, a member coacting with the opposite ends of the tubes in threaded engagement with the helical tube and in end thrust engagement with the longitudinally slotted tube to exert a 95 stretching tension on the helically slotted tube, and lead actuating means enclosed within the tubes and operated by a relative turning thereof.

5. In a pencil of the class described, a 100 helically slotted tube having a shouldered forward end, a longitudinally slotted tube rotatably mounted on the helical tube in end thrust engagement with its shoulder and normally extending at its opposite end 105 beyond the adjacent end of the helical tube, a screw threaded into the end of the helical tube opposed to its shoulder and having a head in end thrust coaction with the adjacent end of the other tube to enable the 110 screw to exert a longitudinal stretching tension on the helical tube to retain the parts in assembled relation.

6. In a pencil of the class described, a 115 helically slotted tube having a shoulder at its forward end and having its slot extending to and opening without the opposite end thereof, a longitudinally slotted tube mounted on the helical tube in end thrust engagement at its forward end with the helical 120 tube shoulder, the rear end of the helical tube normally terminating short of the adjacent end of the other tube, a screw threaded into the rear end of the helical tube with its head in end thrust contact with the 125 rear end of the other tube to apply a longitudinal stretching tension on the helical tube, and lead actuating means enclosed within the tubes and operated by a relative turning thereof.

7. In a pencil of the class described, a helically slotted tube, a thrust collar mounted on the forward end of the tube and cooperating to form a prolonged tapered surface, a longitudinally slotted tube rotatably mounted on the helical tube in end thrust contact at its forward end with the thrust collar, the outer tube having integral longitudinally extending ribs projecting radially therefrom in circumferentially spaced relation and terminating short of the ends of the outer tubes to provide tubular extensions on the ends of such tube, a second collar mounted on the forward end extension of the outer tube, a tapered tip fitting on and fixed to the tapered surfaces of the helical tube and first collar and extending at its rear end over and having a bearing on the second collar, a barrel fixedly mounted on the ribs of the outer tube and cooperating with the outer tube to form a plurality of lead receiving pockets around the axis of the pencil, means cooperating with the rear ends of the inner and outer tubes to retain them in assembled relation, a member fitting into the rear end of the barrel in closing relation to the lead receiving pockets and threading on to the rear end extension of the outer tube, and lead actuating means disposed within the tubes and actuated by 30 a relative turning thereof.
8. The method of forming a longitudinally slotted and fluted tube for use in magazine pencils of the class described, which consists in extruding metal under 35 pressure in cold form from a die to form a tube of predetermined length having a plurality of longitudinally extending ribs projecting outwardly therefrom and co-extensive in length therewith, milling off 40 the end portions of the ribs to provide tubular end extensions on the tube and forming a longitudinally extending slot in the tube between a pair of ribs.
9. The method of forming a longitudinally slotted and fluted tube for use in magazine pencils of the class described, which consists in extruding metal under 45 pressure in cold form from a die to form a tube of predetermined length having a plurality of longitudinally extending integral ribs projecting outwardly therefrom, and then forming a longitudinally extending slot in the tube between the pair of ribs.

In testimony whereof I have hereunto 55 signed my name to this specification.

CLIFFORD N. JOHNSON.
